United States Patent Office

Des. 207,997
Patented June 27, 1967

207,997

GAME BOARD

Isaac M. Cooper, 1622 Hoe Ave., 10460, and William McDuffie, 34B Clason Point Lane 10472, both of Bronx, N.Y.

Filed June 13, 1966, Ser. No. 2,653

Term of patent 3½ years

(Cl. D34—5)

Fig. 1.

Fig. 2.

The dominant features of our design reside in the full line portions shown.

We claim:

The ornamental design for a game board, substantially as shown and described.
